CLAIM

The ornamental design for a tea leaves grinder, as shown and described.

DESCRIPTION

FIG. 1 is a front, right perspective view of a tea leaves grinder showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a rear, left perspective view thereof.

(Continued)

The portions of the Figures shown in broken lines are shown for illustrative purposes only and form no part of the claimed design.

1 Claim, 7 Drawing Sheets
